UNITED STATES PATENT OFFICE.

HARRY H. WISTER, OF DOUGLAS, WYOMING.

WATER-MOTOR.

1,356,421.

Specification of Letters Patent.

Patented Oct. 19, 1920.

Application filed November 13, 1919. Serial No. 337,713.

To all whom it may concern:

Be it known that I, HARRY H. WISTER, a citizen of the United States, residing at Douglas, in the county of Converse and State of Wyoming, have invented a new and useful Water-Motor, of which the following is a specification.

This invention relates to new and useful improvements in water motors, and more particularly to constructions especially adapted for use as current motors.

The primary object of the invention is to provide novel means including an endless chain of water vanes influenced by the current of the water contacting therewith, for rotating gear wheels and causing the operation of predetermined machinery.

A further object of the invention is to provide a frame construction which will permit the device to have connection with a derrick or other hoisting means, whereby the device may be lifted, and easily removed from the body of water on which the motor is operating.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 illustrates a side elevation view of a current motor constructed in accordance with the present invention.

Fig. 2 illustrates a transverse sectional view taken on line 2—2 of Fig. 1.

Fig. 3 illustrates a fragmental plan view of the forward portion of the motor.

Referring to the drawing in detail, the reference character 5 designates the side bars of the frame, which are connected at the front and rear ends thereof by the transversely extending bars 6, connected thereto by any suitable means, such as the bolts 7, passing through registering openings in the side bars 5 and end bars 6.

Disposed adjacent the respective ends of the frame, are the vertically extending bars 8, disposed in parallel relation with each other, the bars 8 adjacent the forward portion of the frame being relatively longer

than the bars 8 disposed at the rear of the frame, for purposes to be hereinafter more fully described.

The upper ends of these bars 8, are connected by the transversely extending bars 9, which are provided with the eye bolts 10, which pass through suitable openings in the bars 9, and receive the nuts 11, whereby the eye bolts 10 are secured to the bars 9 against displacement. It will thus be seen that the hooks, which are employed in connection with derricks may be readily engaged within the eyes of the eye bolts 10, in the event that it becomes necessary to remove the motor from the water on which the same is operating, for purposes of repair.

Supported adjacent the lower end of each of the vertically extending bars 8, are the tubular floats 12 and 13, the same being formed of metal, the forward portions thereof being tapered as at 14, to direct the flow of water between the floats 12 which as shown are disposed in spaced parallel relation with each other. The supporting bands 15, have their ends connected to the side bars 8 by means of the bolts 16, the intermediate portions of said bands, being curved as at 17 the curvature of the band being such as will permit the same to properly embrace the floats 12 and 13, so that the floats are secured to the bars 8, and prevented from movement with relation thereto.

Each of the side members 5, includes a pair of spaced rods 18 and 19, between which are supported the movable bearings 20, and the stationary bearings 21, the movable bearings 20 being controlled by the set screws 22 which operate through threaded openings formed in the bars 23 supported on opposite sides of the bearings in such position that the inner ends of the set screws 22 will engage therewith. It will thus be seen that by operating the set screws 22, the bearings 20, may be moved longitudinally of the bars 18 and 19, to accomplish the adjustment of the bearings 20 with relation to the stationary bearings 21.

Operating in the bearings 21, is the horizontally disposed shaft 24, which shaft has keyed or otherwise secured thereto, the relatively large gear wheels 25, over which operate the endless chains 26, which chains also operate over the gear wheels 27, which are of a diameter equal to the diameter of the gear wheels 25, and are supported by

the shaft 28, operating in the movable bearings 20. From the foregoing it is obvious that adjustment of the bearings 20 results in the loosening or tightening of the end-
less chains 26, to cause the same to properly operate to accomplish their power generating result.

These chains 26, operate in parallel relation with each other, and provide supports for the water vanes 29, which are curved as at 30, to provide scoops, so that the water contacting therewith is prevented from passing over the ends of the vanes, until the vanes have reached end of their rearward movement, thus the vanes 29 receive the entire force of the current of the water contacting therewith.

As shown, the vanes are disposed in spaced relation with each other throughout the lengths of the chains 26 and are secured thereto in any suitable manner which will support the vanes in an upright position, and prevent the same from lateral movement with relation to the chains supporting the same.

The gear wheel 31, is keyed or otherwise secured to the shaft 24, and has connection with the shaft 32, through the sprocket wheel 33, secured adjacent one end of the shaft 32, together with the chain 34, operating over the gear wheels 31 and sprocket wheel 33, the shaft 32, being supported in the bearings 35 and 36, provided in the relatively long bars 8, one end of said shaft 32, having connection with a drive shaft not shown, and which has connection with suitable machinery, not shown, and to be operated by the power generated by the current motor.

It is of course understood that the motor, in operation, should be anchored or otherwise positioned mid-stream, or at a point in the stream where the current is the greatest, so that the water of the stream will

properly contact with the vanes for causing the operation of the gear wheels of the motor.

It is believed that in view of the foregoing, the construction and operation of the device will be clearly obvious and that a detail description of the operation step by step, is unnecessary for a complete understanding of the invention.

It might, however be stated that the construction of the floats 12, is such that the vanes 29, which are contacting with the water, are held submerged.

Having thus described the invention, what is claimed is:—

A current motor including a frame, floats for supporting the frame, vertically extending bars positioned adjacent to one end of the frame, and forming a part thereof, a shaft supported by the vertically extending bars, pairs of spaced horizontally disposed bars having connection with the first mentioned bars, movable bearings disposed between the latter bars, means for moving the bearings, a shaft operating in the bearings, a pair of spaced gear wheels secured to the latter shaft, a horizontally disposed shaft positioned adjacent to the opposite end of the frame, a pair of spaced gear wheels operating thereon, endless chains moving over the gear wheels, a plurality of vanes connecting the chains and being curved transversely of their lengths, the chains being disposed in spaced relation with each other, and means for transmitting movement of the chains to the first mentioned shaft.

In testimony that I claim the foregoing as my own, I have hereto affixed my signature in the presence of two witnesses.

HARRY H. WISTER.
